DESIGN FOR A BOTTLE STERILIZER

Clarence A. Godshalk, Ardmore, Pa., assignor to
Godshalk Company, Philadelphia, Pa., a cor-
poration of Pennsylvania

Application June 9, 1936, Serial No. 63,179

Term of patent 14 years

To all whom it may concern:

Be it known that I, Clarence A. Godshalk, a citizen of the United States, residing at Ardmore, in the county of Montgomery and State of Pennsylvania, have invented a new, original, and ornamental Design for a Bottle Sterilizer, of which the following is a specification, reference being had to the accompanying drawing, forming part thereof.

Figure 1 is a top plan view of a bottle sterilizer embodying my invention, and

Figure 2 is a side elevation of the sterilizer.

I claim:

The ornamental design for a bottle sterilizer, as shown.

In testimony whereof I have hereunto signed my name.

CLARENCE A. GODSHALK.
